(57) **CLAIM**

The ornamental design for a convertible garment, as shown and described.

DESCRIPTION

FIG. 1 is a front elevation view of a convertible garment, showing our new design, when the convertible garment is in an unconverted position;

FIG. 2 is a back elevation view thereof, when the convertible garment is in an unconverted position;

FIG. 3 is a front elevation view thereof, when the convertible garment is in a converted position;

FIG. 4 is a back elevation view thereof, when the convertible garment is in a converted position;

FIG. 5 is a side view of the bottom portion of the convertible garment in an unconverted position and the opposite side being a mirror image;

FIG. 6 is a side view of the bottom portion of the convertible garment in a converted position and the opposite side being a mirror image;

FIG. 7 is a side view of the sleeve portion of the convertible garment in an unconverted position and the opposite side being a mirror image;

FIG. 8 is a side view of the sleeve portion of the convertible garment in a converted position and the opposite side being a mirror image;

FIG. 9 is a front elevation view of a second embodiment of a convertible garment, showing our new design, when the convertible garment is in an unconverted position;

FIG. 10 is a back elevation view thereof, when the convertible garment is in an unconverted position;

FIG. 11 is a front elevation view thereof, when the convertible garment is in a converted position;

FIG. 12 is a back elevation view thereof, when the convertible garment is in a converted position;

FIG. 13 is a side view of the bottom portion of the convertible garment in an unconverted position and the opposite side being a mirror image;

(Continued)

FIG. 14 is a side view of the bottom portion of the convertible garment in a converted position and the opposite side being a mirror image;

FIG. 15 is a side view of the sleeve portion of the convertible garment in an unconverted position and the opposite side being a mirror image; and,

FIG. 16 is a side view of the sleeve portion of the convertible garment in a converted position and the opposite side being a mirror image.

The broken lines in FIGS. 1-9 and 12-14 illustrate portions of the convertible garment that form no part of the claimed design.

The broken lines immediately adjacent the stippled areas in FIGS. 10-11 and 15-16 represent the bounds of the claimed design while all other broken lines in FIGS. 10-11 and 15-16 illustrate portions of the convertible garment that form no part of the claimed design.

The stippling and/or line shading in FIGS. 9-16 represent contrast in materials.

1 Claim, 16 Drawing Sheets
